UNITED STATES PATENT OFFICE.

WALTER G. E. HARVEY, OF NORTH BERGEN, NEW JERSEY.

CASTING-MACHINE.

1,320,228.

Specification of Letters Patent. Patented Oct. 28, 1919.

Application filed November 29, 1918. Serial No. 264,495.

To all whom it may concern:

Be it known that I, WALTER G. E. HARVEY, a citizen of the United States, and residing at North Bergen, in the county of Bergen and State of New Jersey, have invented certain new and useful Improvements in Casting-Machines, of which the following is a specification, such as will enable those skilled in the art to which it appertains to make and use the same.

This invention relates to metal casting machines and particularly to machines of this class known as "compressed air casting machines" designed to be used especially by dentists in the casting of inlays, saddles, full and partial plates, and bridges, and said machine may also be used by jewelers and others in the casting of small or comparatively small metallic parts; and the object of this invention is to provide a machine of the class specified with which both coal gas and nitrous oxid may be used in melting the metal employed; a further object being to provide a common means whereby an air-tight joint or connection may be produced with each of the different size rings employed in machines of this class; a still further object being to provide automatic means for shutting off the supply of coal gas or nitrous oxid and for opening the compressed air supply in the operation of the machine; and with these and other objects in view the invention consists in a machine of the class and for the purpose specified which is simple in construction and operation and efficient in use.

The invention is fully disclosed in the following specification, of which the accompanying drawing forms a part, in which the 40 separate parts of my improvement are designated by suitable reference characters in each of the views, and in which:—

Figure 1 is a sectional side view of my improved machine indicating the parts thereof in a normal position and illustrating one method of its operation;

Fig. 2 a plan view of the construction as shown in Fig. 1;

Fig. 3 a partial section on the line 2—2 of Fig. 2 but showing parts in a position indicated in dotted lines in Fig. 4;

Fig. 4 a front view of the machine as shown in Figs. 1 and 2 and indicating parts thereof in a different position in dotted lines;

Figs. 5, 6 and 7 are views similar to Fig.

1 but showing only a part of the construction and illustrating modified uses of the machine;

Fig. 8 a view similar to Fig. 4 but showing only a part of the construction and illustrating a modification; and,

Fig. 9 a detail sectional view of a crucible form which I employ in the method of operation as illustrated in Figs. 1 to 4 inclusive.

In the practice of my invention, I provide a frame 10 which consists, in the form of construction shown, of a base portion 11 at one end of which is an upright goose-neck portion 12 having a hollow cylindrical head portion 13, which ranges vertically. The base 11 of the frame is provided with a raised annular flange 14, the center of which is provided with an aperture 15 which is in common alinement with the center of the aperture on the head portion 13, and the frame 10 or the base 11 thereof is secured to a table or support 16 by a plurality of screws 17.

A plunger 18 is mounted in the head 13 and movable vertically by means of a lever 19 placed in a vertical recess 20 in the top of the goose-neck portion 12 and pivoted to said gooseneck as shown at 21. The pivoted end of the lever 19 is provided with a circular head 22, the periphery of which is provided with a plurality of teeth or projections 23, which mesh with a rack 24 countersunk and secured in the inner face of the plunger 18 by screws 25. The front end of the lever 19 is tapered as shown at 26 and a hand-piece 27 is secured thereto by a cylindrical nut 28 mounted on the end of the lever 19.

A pawl or clutch member 29 is secured to the gooseneck 12 of the frame by means of a casing 30 in which said pawl is moved vertically by a spring 31, and a sleeve 32 is mounted over the casing and movable longitudinally thereof, and connected with the pawl 29 by a screw 33 which is movable in an elongated slot 34, and with this construction the lever 19 will be locked against movement in the direction of the arrow α of Fig. 1 by the pawl 29 unless said pawl is moved downwardly by grasping the sleeve 32 as will be readily understood, and when the lever 19 is moved in the direction of the arrow α^2 of Fig. 1, as hereinafter described, said lever as well as the plunger 18 will be locked against movement by the engagement of the pawl 29, or the nose 35

thereof with the teeth or projections 23 on the head 22 of the lever 19.

The plunger 18 consists of a top portion 36 with which the rack 24 is connected and 5 a bottom sleeve portion 37 having a detachable cap 38 carrying a stuffing box 39. At one side of the sleeve portion 37 is a nozzle 40 with which is connected a flexible tube 41 which also connects with a suitable compressed air supply device which is not shown, and the port or passage 42 of the nozzle 40 is normally closed by the head 43 of a valve 44 mounted in the sleeve portion 37, said valve being normally depressed by 10 a spring 45 mounted in the sleeve portion 37 between the valve 44 and the bottom of the top portion 36 of the plunger, as clearly shown in Figs. 1 and 3; and it will be noted that the head 43 of the valve 44 normally 15 seats on an annular flange 46 within the sleeve portion 37 below the nozzle 40.

The valve 44 is provided with a downwardly directed tubular portion 47 secured to the head 43 as shown at 48, the base of 20 the tubular portion 47 being enlarged as shown at 49 and provided with a reduced threaded portion 50 with which is connected a circular lid or cover 51 and a conical aperture 52 is formed in the central bottom portion 25 of the lid or cover 51 and the reduced threaded portion 50 of the valve 44.

An air distributor 53 is secured to the bottom of the tubular portion 47 of the valve, said distributor having a plurality of horizontal apertures 54 communicating with a vertical aperture 55 which communicates with the aperture in the tubular portion 47, and said tubular portion is provided in the top thereof with a plurality of apertures 56, 30 which when the valve 44 is in its raised position as shown in Fig. 3 are placed in communication with the port or passage 42 in the nozzle 40 by a chamber 57 in the sleeve portion 37. With this construction 35 compressed air passes from the tube 41 through the nozzle 40, the apertures 56 through the tubular portion 47 and the apertures 55 and 54 in the distributor 53 and out through the conical aperture 52 in the lid 40 or cover 51 in the form of an annular spray.

A radially directed finger 58 is secured between the lid 51 and valve 44, or the enlarged portion 49 thereof, and the free end of said finger extends beyond the lid or 55 cover 51 and is provided with a downwardly directed curved portion 59, as clearly shown in Fig. 4. The bottom face of the lid or cover 51 is provided, in the construction shown, with three annular grooves 60 which 60 are so formed as to retain strips of asbestos or similar substance 61 treated with graphite or similar substance.

One side of the plunger 18 or the top portion 36 thereof is provided with a longitudinal slot 62, and a pin or screw 63 is passed

through the corresponding side of the head 13 of the frame and into said slot, and by this construction serves to hold the plunger 18 against rotation in its vertical movement through said head.

The upwardly directed flange 14 on the base 11 forms a recess 64 into which one of a number of casting rings may be supported and, in the construction shown in Figs. 1 to 4 inclusive, I have shown at 65 what is known as an inlay casting ring which is mounted or supported on the base 11 within the recess 64 by an annular raised stand 66 having a recess 67 in the top face thereof to receive the bottom portion of the ring 65, stand 66 being provided centrally with an aperture 68 which forms a communication between the casting ring and the aperture 15 in the base 11. The stand 66 is held centrally of the recess 64 by a guide ring 69 which centers the stand 66 in the recess 64, said guide ring being provided with a thumb and finger piece 70 to permit of its placement in and removal from the recess 64.

In Fig. 1 of the accompanying drawing 90 the inlay ring 65 is shown partially prepared and in a condition ready for the melting of the metal employed prior to forming the casting or, in other words, said ring is provided with an inlay mold 71 formed by 95 a molding wax embedded in an investment 72, and said molding wax is burned out in the usual manner to form the inlay mold, and a vertical sprue way 73 is also formed in the investment in the usual manner to 100 permit of the passage of metal downwardly into the inlay mold 71. The sprue way 73 communicates with a concavo-convex portion 74 in the top of the investment which is formed by a crucible former 75 similar to that shown in Fig. 9 of the drawing. The crucible former 75 consists of an annular disk 76 at one side of which is a projecting semi-spherical portion 77 having an annular shoulder 78, and the semi-spherical portion 77 is provided centrally with a deep aperture 79 into which a sprue wire connected with a wax model of an inlay may be placed in order to support said model while embedding the same in an investment in the 115 usual manner.

In Figs. 1 to 4 inclusive, I have shown a coal gas blow-pipe 80 supported in the base 11 of the frame, or an extension 81 thereof by a bent rod 82, which is forked at its upper 120 end as shown at 83. Within the forked end 83 is pivoted a valve device 84 having oppositely directed tubular extensions 85 and 86, and the coal gas blow-pipe 80 is shown connected with the extension 85. A flexible 125 coal gas supply pipe 87 is connected with the extension 86 as illustrated in Fig. 2 of the drawing, and an air supply pipe 88 is mounted on top of the blow-pipe 80 and passes into and centrally through the dis- 130

charge end of said blow-pipe as shown at 89 in Fig. 4 of the drawing. A flexible pipe 90 is connected with the air supply pipe 80 and serves to supply air to the pipe 88 and 5 discharge it through the open end of the coal gas blow-pipe in the usual manner.

It will be noted on a consideration of Fig. 4 of the drawing that the finger 58, or the curved end 59 thereof, bears upon the top of 10 the blow-pipe 80, or the pipe 88 and is secured thereto when the machine is in its normal position, and after the coal gas flame from the blow-pipe 80 has heated the gold or other metal 91 in the concavo-convex recess 74 at the top of the investment 72 to bring said metal into a molten state, the lever 19 is grasped by the hand of the operator and moved forwardly into the position indicated in dotted lines in Fig. 1 in which 20 operation the lid or cover 51, the valve 44 and plunger 18 are moved downwardly and the lid or cover is compressed upon the top of the inlay ring 65 under the tension of the spring 45.

25 In the above operation the top of the inlay ring 65 engages the inner annular recess 60 in the bottom of the lid or cover 51, or the asbestos 61 therein, and this forms an air-tight connection between the top of the ring 65 and the lid or cover 51, and in the downward movement of the plunger 18 with the various parts connected therewith, and after the lid or cover 51 engages the top of the ring 65 the continuation of the downward movement of the plunger 18 by the lever 19 will cause the valve 44 or the head 43 thereof to move upwardly in the sleeve portion 37 against the tension of the spring 45 into the position shown in Fig. 3 of the 40 drawing, in which position compressed air is admitted through the nozzle 40, through the apertures 56, through the tubular sleeve portion 47 and out through and at the opposite sides of the air distributor 53. The compressed air discharged around the distributor 53 forces the molten metal 91 through the sprue way 73 and into the inlay mold 71 in the investment 72. The investment 72 is composed of porous material, 50 and in the above operation of forcing the molten metal 91 into the mold 71, the air previously in said mold will be forced through the investment and through the apertures 68 and 15 in the stand 60 and base 55 11 respectively.

When the lever 19 has been moved forwardly to depress the lid or cover 51 onto the top of the inlay ring 65 and under the tension of the spring 45 or as illustrated in 60 Fig. 3 of the drawing, said lid or cover is held in this position by the engagement of the pawl 29 with the teeth 23 on said lever and compressed air under a predetermined pressure may be constantly introduced into 65 the top of the inlay ring to force the molten

metal into the mold and to prevent said metal from moving backwardly, or upwardly through the sprue way, while it is cooling or setting and in this way a perfect inlay casting is made in the mold 65.

70 In the above operation of moving the plunger 18 downwardly by the lever 19, the finger 58 moves the blow-pipe 80 downwardly into the position indicated in dotted lines in Fig. 4, which operation shuts off the supply of coal gas to said blow-pipe by reason of the turning of the valve 84 pivoted within the forked end 83 of the rod 82, and this blow-pipe will remain in the position indicated in dotted lines until moved upwardly by hand to the position shown in full lines in Fig. 4, and is ignited in the usual manner. In other words the operation of depressing the plunger 18, after the metal 91 has been heated to a molten state 85 automatically shuts off the coal gas supply and opens the valve 44 to admit compressed air into the top portion of the inlay ring 65.

80 It will be noted from Fig. 2 of the drawing, that the lever 19 is normally held in its 90 inoperative position as shown in Figs. 1 and 2, by a pin 92, which projects into the recess 20 and engages on side of the lever 19 as shown in Fig. 2, said pin being normally forced inwardly by a spring 93 secured to 95 the side face of the gooseneck 12 by a screw 94.

95 In Fig. 8 of the drawing, I have shown a nitrous oxid blow-pipe 95 secured to the tubular extension 85 of the valve 84 in place 100 of the coal gas blow-pipe 80, and it will be understood that either of these blow-pipes may be employed at will by the operator, by simply detaching one and substituting the other therefor, as both coal gas and nitrous oxid are commonly used by dentists and others in the melting of gold or other metal used in forming or casting inlays, bridges, plates and the like.

105 In Figs. 5, 6 and 7 of the drawing, I have 110 shown different forms of casting rings which may be substituted for the inlay ring 65 in producing castings of different sizes, as well as of different characters and in Fig. 5 of the drawing, I have shown a deep casting ring 96 which fits in the recess 67 within the upwardly directed flange 14 of the base 11 and said ring is of such height that the top face 97 thereof would be in a plane similar to the plane of the top face of the inlay ring 65 and, in practice, I provide an annular groove 98 in the inner wall of the ring 96 adjacent to the top edge 97 thereof which forms a guide to inform the operator or user as to the height of the investment 115 120 to be placed in such ring. When the ring 96 is employed in the machine the top face 97 thereof will operate in connection with the outer annular groove 60 in the lid or cover 51, or the asbestos therein, to form an 130

air-tight connection in the same manner as with the ring 65.

In Fig. 6 of the drawing, I have shown a casting ring 99 of the same diameter as the ring 96 but shallower in form, and which operates in connection with the outer recess 60 in the lid or cover 51, and in order to bring the top face 100 of the ring 99 to the same horizontal plane as the top face 97 of the ring 96, I employ a supplemental base 101 which fits within the recess 64 in the upwardly directed flange 14 of the base 11 of the frame, and said supplemental base 101 is provided in the top with a recess 102 into which the ring 99 fits and centrally of the supplemental base 101 is an aperture 103, which communicates with the aperture 15 in the base 11. The inner face of the ring 99 is provided adjacent to the top edge 100 with an annular groove 104 similar in all respects to the groove 98 in the ring 96.

In Fig. 7 of the drawing, I have shown at 105 a medium size casting ring, the diameter of which is such as to operate in connection with the intermediate annular recess 60 in the lid or cover 51, and the depth of which is similar to that of the ring 99 shown in Fig. 6 and this ring is used in connection with the supplemental base 101 but is supported centrally of the recess 102 in the top of the base 101 by the guide ring 69 shown in Figs. 1 to 4 inclusive. The top face 106 of the ring 105 is in the same plane as the rings 99, 96 and 65 and the inner face of the ring 105 is also provided with an annular groove 107 adjacent to the top edge thereof.

It will be noted from the accompanying drawing that the lid or cover 51 is adapted for use in connection with any of the casting rings 65, 96, 99 and 105 and regardless of which of these rings is employed in the operation of casting inlays, bridges, plates and the like, an air-tight connection is formed between the top of the ring employed and the bottom face of the lid or cover 51 thus preventing the leakage of the compressed air employed for forcing the molten metal into the mold in the investment.

It will be readily understood that my invention is not limited to the material employed in the formation of the investment, or any specific method of forming the mold in the investment, as this feature of the apparatus is old and well-known and commonly practised by dentists and others. The chief features of my invention are the provision of a lid or cover which is adapted for use in connection with casting rings of any kind or class, means for melting metal employed by a coal gas blow-pipe, or a nitrous oxid blow-pipe, means for automatically shutting off the supply of coal gas or nitrous oxid in the descent of the

plunger and for automatically opening the supply of compressed air, as well as the provision of means for automatically holding the apparatus in its operative position, and while I have shown various details of construction for carrying my invention into effect, it will be understood that various changes therein and modifications thereof may be made, within the scope of the appended claims, without departing from the spirit of my invention or sacrificing its advantages.

Having fully described my invention, what I claim as new and desire to secure by Letters Patent, is:—

1. In a machine of the class described, a frame, means for supporting a casting ring in said frame, a plunger mounted to move vertically in said frame, a valve carried by said plunger, a cover member carried by said valve, tensional means for holding said valve normally in a closed position, and means for operating the plunger to move it vertically in the frame and to open said valve.

2. In a machine of the class described, a frame, a plunger mounted to move vertically in said frame, a compressed air supply connected with one end portion of the plunger, a valve in said end of the plunger for controlling the passage of air into and through the plunger, tensional means for holding said valve normally in a closed position, a cover member carried by said valve, means for moving the plunger vertically in the frame, and means for locking said plunger and said last named means in different positions.

3. In a machine of the class described, a frame, a casting ring supported on said frame, a plunger mounted to move vertically in said frame and in vertical alignment with said casting ring, a tensionally operated valve in said plunger, a cover member carried by said valve, a pivoted blow-pipe support and supply device mounted at one side of the frame, means for supplying compressed air to the plunger, said supply being normally closed by said valve, an air distributor mounted in the bottom face of the cover member, and means for moving the plunger downwardly to bring the cover member into engagement with the top face of the casting ring mounted on the frame and to move the plunger downwardly over said valve to admit compressed air into said plunger and through said valve.

4. In a machine of the class described, a frame, a casting ring supported on said frame, a plunger mounted to move vertically in said frame and in vertical alignment with said casting ring, a tensionally operated valve in said plunger, a cover member carried by said valve, a pivoted

- blow-pipe support and supply device mounted at one side of the frame, means for supplying compressed air to the plunger, said supply being normally closed by said valve, an air distributor mounted in the bottom face of the cover member, means for moving the plunger downwardly to bring the cover member into engagement with the top face of the casting ring mounted on the frame and to move the plunger downwardly over said valve to admit compressed air into said plunger and through said valve, and means carried by the valve and cover member for closing the blow-pipe support and supply device in the downward movement of said plunger.
5. In a machine of the class described, a frame, a casting ring supported on said frame, a plunger mounted to move vertically in said frame and in vertical alignment with said casting ring, a tensionally operated valve in said plunger, a cover member carried by said valve, a pivoted blow-pipe support and supply device mounted at one side of the frame, means for supplying compressed air to the plunger, said supply being normally closed by said valve, an air distributor mounted in the bottom face of the cover member, means for moving the plunger downwardly to bring the cover member into engagement with the top face of the casting ring mounted on the frame and to move the plunger downwardly over said valve to admit compressed air into said plunger and through said valve, and means for automatically locking said plunger and said last named means against upward movement.
6. In a machine of the class described, a frame, means for supporting a plurality of different size casting rings in said frame, a plunger mounted in said frame and adapted to move toward and from the casting ring supported by the frame and in axial alignment therewith, a cover member carried by said plunger, the bottom face of said cover member being provided with a plurality of annular recesses having asbestos packings therein, and means for moving said plunger downwardly to bring said cover member or an annular packed recess thereof into engagement with the top edge of a casting ring supported by the frame.
7. In a machine of the class described, a frame, means for supporting a plurality of different size casting rings in said frame, a plunger mounted in said frame and adapted to move toward and from the casting ring supported by the frame and in axial alignment therewith, a cover member carried by said plunger, the bottom face of said cover member being provided with a plurality of annular recesses having asbestos packings therein, means for supplying compressed air to said plunger, a tensionally controlled valve for normally closing said supply to said plunger, means for moving said plunger downwardly to bring said cover member into engagement with a casting ring supported by the frame which operation opens the valve device to admit compressed air into the plunger, and means for discharging said air admitted into the plunger through the bottom face of said cover member, and means for automatically locking said plunger, valve and cover member in said last named position.
8. In a machine of the class described, a frame, means for supporting a plurality of different size casting rings in said frame, a plunger mounted in said frame and adapted to move toward and from the casting ring supported by the frame and in axial alignment therewith, a cover member carried by said plunger, the bottom face of said cover member being provided with a plurality of annular recesses having asbestos packings therein, means for supplying compressed air to said plunger, a tensionally controlled valve for normally closing said supply to said plunger, means for moving said plunger downwardly to bring said cover member into engagement with a casting ring supported by the frame which operation opens the valve device to admit compressed air into the plunger, means for discharging said air admitted into the plunger through the bottom face of said cover member, and means for automatically locking said plunger, valve and cover member in said last named position.
9. In a machine of the class described, a frame, means for supporting a plurality of different size casting rings in said frame, a plunger mounted in said frame and adapted to move toward and from the casting ring supported by the frame and in axial alignment therewith, a cover member carried by said plunger, the bottom face of said cover member being provided with a plurality of annular recesses having asbestos packings therein, means for supplying compressed air to said plunger, a tensionally controlled valve for normally closing said supply to said plunger, means for moving said plunger downwardly to bring said cover member into engagement with a casting ring supported by the frame which operation opens the valve device to admit compressed air into the plunger, means for discharging said air admitted into the plunger through the bottom face of said cover member, and means for automatically locking said plunger, valve and cover member in said last named position.
10. In a machine of the class described, a frame, means for supporting a plurality of casting rings in said frame, a plunger

mounted in said frame and adapted to move toward and from the casting ring supported by the frame and in axial alinement therewith, means for holding said plunger normally in a raised position, a cover member carried by said plunger, the bottom face of said cover member being provided with a plurality of annular packed recesses, means for supplying compressed air to said plunger, said supply being normally closed, means for moving the plunger downwardly to bring said cover member into engagement with a casting ring supported by the frame which operation automatically opens 10 the supply of compressed air to the plunger, means for discharging the compressed air supplied to the plunger through and around an air distributor secured in the bottom face of the cover member, a blow-pipe pivotally supported at one side of the frame, means for automatically shutting off the supply to said blow-pipe in the downward movement of the plunger, and means for locking said 15 plunger and said cover member against upward movement when in its depressed position.

11. A casting machine of the class described, comprising a frame consisting of a base and upright gooseneck portion having a vertical cylindrical head, means involving the base for supporting casting rings thereon, a plunger mounted in the cylindrical head of the gooseneck portion of the frame, a lever pivoted within the top of the gooseneck portion of the frame, a rack secured in the plunger, the pivoted end of said lever being provided with a plurality of teeth or projections adapted to coöperate with the rack in said plunger to move it vertically, a spring depressed valve device mounted in the lower end portion of the plunger, means for admitting compressed air to said end of the plunger, said means being normally closed by said valve device, said valve device extending beyond the end of the plunger and a cover member mounted on the extension of said valve, an air distributor countersunk in said cover member and secured in the extension of the valve, a pivoted blow-pipe support and supply device mounted at one side of the frame, means carried by said valve device and said cover member for

depressing said blow-pipe support and supply device in the downward movement of the plunger, a pawl device secured in the gooseneck portion of the frame and operating in connection with the teeth or projections on the pivoted end of said lever for locking the same against movement in one direction, and means for preventing the rotation of said plunger in its vertical movement. 55 60

12. A casting machine of the class described, comprising a frame, means for supporting one of a number of casting rings of different heights and diameters in said frame, a cover member mounted to move toward and from a casting ring supported in said frame, and means on said cover member for forming an air-tight connection between the same and the top of the casting ring supported on said frame. 65 70

13. In a casting machine of the class described, a cover member provided with a plurality of circular ring seats, one of said ring seats being adapted to form an air-tight connection with any one of a number of casting rings of different sizes supported beneath said cover member and in axial alinement therewith. 75

14. A casting machine of the class described comprising a frame, means for supporting a casting ring on said frame, a plunger mounted to move toward and from said casting ring, a cover member carried by said plunger and adapted to form an air-tight closure for the top of the casting ring, a pivoted blow-pipe support and supply device mounted at one side of the frame, means for connecting either a coal gas or nitrous oxid blow-pipe with said support and supply device, and a finger carried by the plunger for automatically moving the blow-pipe into an inoperative position in the downward movement of said plunger. 80 85 90 95

In testimony that I claim the foregoing as my invention I have signed my name in presence of the subscribing witnesses this 27th day of November, 1918.

WALTER G. E. HARVEY.
